**BOLT MECHANISM INCLUDING A PAIR OF
EXTRACTORS FOR A FIREARM**

Frederick P. Reed, Ludlow, Mass., assignor to the United States of America as represented by the Secretary of the Army

Filed Sept. 10, 1962, Ser. No. 222,745

7 Claims. (Cl. 42—25)

(Granted under Title 35, U.S. Code (1952), sec. 266)

The invention described herein may be manufactured and used by or for the Government for governmental purposes without the payment to me of any royalty thereon.

This invention relates to bolt mechanisms for firearms and more particularly to the firing pin cocking, the extractor and the ejector devices carried thereby.

It is one object of this invention to provide for a firearm, which is expendable, a bolt mechanism which is simple in design and economical to manufacture yet positive in operation.

It is a further object of this invention to provide a bolt assembly in which the firing pin spring also acts as an extractor spring and in which the extractors act as the ejector through the cooperation of the extractors with the bolt buffer, whereby the extractors open up to release the fired case when the bolt contacts the buffer.

It is a further object of this invention to provide such a bolt mechanism wherein the firing pin is cocked by action of the bolt return spring when the bolt is adjacent its recoil position.

The specific nature of the invention as well as other objects and advantages thereof will clearly appear from a description of a preferred embodiment as shown in the accompanying drawings in which:

FIG. 1 is a longitudinally cross-sectioned view of the front end of the firearm receiver and shows the bolt in battery position;

FIG. 1a is a rearward continuation of FIG. 1;

FIG. 2 is an enlarged view taken along line 2—2 of FIG. 1;

FIG. 3 is an enlarged view taken along line 3—3 of FIG. 2;

FIG. 4 is an enlarged view taken along line 4—4 of FIG. 1;

FIG. 5 is an enlarged view taken along line 5—5 of FIG. 3;

FIG. 6 is a fragmentary, longitudinally cross-sectioned view of the rear end of the receiver showing the bolt in the recoil position and the fired case in the ejection port;

FIG. 7 is an enlarged view taken along line 7—7 of FIG. 6;

FIG. 8 is a view similar to FIG. 7 but cut in a longitudinal section;

FIG. 9 is a view similar to FIG. 8 but showing the bolt displaced forwardly of the recoil position in its counter-recoil stroke and the firing pin cocking lever in contact with the cocking lever stop;

FIG. 10 is a view similar to FIG. 9 but showing the bolt advanced further towards battery position and the firing pin cocking lever in contact with the cocking lever release pin; and

FIG. 11 is a view similar to FIG. 10 but showing the bolt advanced still further towards battery position with

2

the firing pin cocking lever released from cocking lever stop and the firing pin held cocked by the sear.

Shown in the figures is a firearm 12 having a tubular receiver 14 with a barrel 16 mounted in the front end thereof. Cartridges 18 are fed sequentially from a magazine 20 into receiver 14 at a position to be picked up by a reciprocal bolt assembly 22, during counterrecoil travel to a battery position, for chambering and discharge in barrel 16. Fired case 24 of cartridge 18 is ejected out

10 a port 25 formed in the underside of receiver 14, rearwardly of magazine 20, after being carried by bolt assembly 22 to the recoil position thereof in the receiver.

A cylindrical buffer 26 extends forwardly into receiver 14 from the rear end thereof for contact by the rear 15 end of bolt assembly 22 to stop recoil displacement thereof at the recoil position. A coiled return spring 28 is disposed between the rear end of bolt assembly 22 and the rear end of receiver 14 for biasing the bolt assembly 22 to battery position. Buffer 26 extends into spring 28 to 20 provide support therefor when compressed.

Bolt assembly 22 includes a bolt 30 having a stepped bore 32 which extends axially therethrough and forms a rearwardly facing annular shoulder 34. The front end of bore 32 communicates with a recess 36 formed in the 25 front end of bolt 30 to receive the base of case 24. Recess 36 extends upwardly from the underside of bolt 30 to permit downward displacement of the base of case 24 from a position concentric with bore 32, for ejection of the case through ejection port 25, as hereinafter described.

Slidably mounted in bore 32 is a firing pin 40 having a cylindrical body portion 42 with a striker portion 44 of smaller diameter extending forwardly therefrom. A spring 46 is disposed in bore 32 rearwardly of body portion 42 for biasing firing pin 40 forwardly to a striking position wherein the front end of the body portion is in contact with shoulder 34 and the end of striking portion 44 projects into recess 36. The rear end of spring 46 35 is supported by a pair of extractors 48 pivotally mounted on bolt 30 as hereinafter described.

Extractors 48 are partially received by a pair of corresponding channels 50 which extend along the length of bolt 30 on opposite sides thereof. Channels 50 each include a mouth portion 52 which extends inwardly for 45 communication with bore 32 at the rear end of bolt 30. Each of the extractors 48 is provided with a lug 54 which is received by the corresponding mouth portion 52 and a pin 55 extends vertically through each of the lugs to provide a fulcrum for the lateral displacement of the respective extractor 48. An arm 58 extends from lug 54 along the length of bolt 30 and in the respective ones of the channels 50 so as to protrude from the periphery of the bolt. An arcuate tail section 56 extends from each 50 of the arms so as to curve inwardly over the rear end of bore 32 for contact by the rear end of spring 46 and for contact by the front end of buffer 26 when bolt 30 is in recoil position.

A claw 60 is formed at the front end of each of the 60 arms 58 so as to extend inwardly for engagement with extractor groove 62 of case 24, when the base thereof is positioned in recess 36 in alignment with bore 32, to transfer recoil displacement of bolt 30 to the case and to hold the case extended in axial alignment with the bolt during recoil travel thereof to the recoil position.

Each of the claws 60 is provided with an arcuate face 64 (see FIG. 4) having the same radius as extractor groove 62 so as to prevent vertical displacement of case 24 from recess 36 when the claws are pressed thereagainst. Claws 60 are pressed into resilient engagement with extractor groove 62 by the bias of spring 46 against tail sections 56 which pivot the claws inwardly. The angular relationship of tail sections 56 to arms 58 is slightly more than 90° so that, when the tail sections are in contact with the front end of buffer 26, arms 58 are pivoted outwardly to displace claws 60 from engagement with extractor groove 62.

As has been noted hereinbefore, the outer sides of arms 58 protrude from the respective channels 50 along the length thereof. Such protruding portions are slidably received by cooperating slots 65 formed along the inside of receiver 14 to prevent rotational displacement of the bolt assembly 22 around the longitudinal axis thereof during reciprocation. Slots 65 are formed deep enough to permit sufficient displacement of claws 60 to clear the base of case 24 when extractors 48 are pivoted outwardly.

Firing pin 40 is retracted relative to bolt 30 for cocking by a cocking lever 66 which is mounted in body portion 42 at a channel 68 that extends forwardly in the body portion from the rear end thereof. A pin 69 extends through body portion 42 and through the rear end of cocking lever 66 to provide a fulcrum for pivotal displacement thereof. Channel 68 is long enough to receive cocking lever 66 when pivoted downwardly. A spring 70 is operationally disposed on pin 69 for biasing the free end of cocking lever 66 outwardly from channel 68. The outward displacement of cocking lever 66 is limited by contact thereof with a pin 72 which is mounted through body portion 42 so as to traverse channel 68. When in contact with pin 72, the cocking lever 66 extends outwardly and forwardly from channel 68.

The free end of cocking lever 66 extends through a longitudinally elongated opening 73 in bolt 30 into a longitudinal channel 74 formed inside of receiver 14. A cocking lever stop pin 76 extends transversely across channel 74 and is positioned so as to be slightly forward of the free end of cocking lever 66 when bolt 30 is in contact with buffer 26 at the recoil position. Extending transversely across opening 73 adjacent the rear end thereof is a cocking lever release pin 78 which, during forward displacement of bolt 30 relative to firing pin 40, makes camming contact with cocking lever 66 to pivotally displace the cocking lever free of cocking lever stop pin 76. A forwardly facing ledge 80 is formed in body portion 42 for engagement with a sear 82 which is pivotally mounted in bolt 30 for releasably holding firing pin 40 in cocked position and is actuatable by a trigger actuated bar 84 in receiver 14.

Operation

Firearm 12 is fired from the closed bolt position with bolt assembly 22 in battery position and firing pin 40 held cocked by sear 82. Actuation of sear 82 by trigger bar 84 releases firing pin 40 for discharge of cartridge 18 chambered in barrel 16. Firearm 12 is of blowback type and, therefore, the force of discharge displaces case 24 rearwardly which energizes bolt assembly 22 for its cyclic reciprocation.

During the recoil travel of bolt assembly 22, claws 60 grip extractor groove 62 of fired case 24 through the force of spring 46 applied against tail sections 56 of extractors 48. When bolt assembly 22 reaches recoil position, it is stopped by contact of bolt 30 with buffer 26. At the same time, tail sections 56 are also contacted by buffer 26 to cause outward pivotal displacement of extractors 48 to free claws 60 from case 24 which, through the force of gravity, drops through ejector port 25 during reduced velocity of bolt assembly 22. Also, when bolt assembly 22 is adjacent recoil position the free end of cocking lever 66 snaps over in back of cocking lever stop pin 76 (FIG. 8).

Spring 28, which was compressed by bolt assembly 22 during recoil travel thereof, reacts against bolt 30 for displacement thereof in counterrecoil travel to battery position. However, firing pin 40 is held against displacement with bolt 30 by the contact of cocking lever 66 with cocking lever stop pin 76 (FIG. 9) so that the bolt moves forwardly relative to the firing pin, compressing spring 46. When bolt 30 is displaced to where firing pin 40 is in the cocked position relative thereto, cocking lever release pin 78 contacts cocking lever 66 to cam the cocking lever free of cocking lever stop pin 76, whereby the firing pin is released into engagement by sear 82 and is held cocked thereby during continued forward travel of bolt assembly 22 (FIG. 11). As bolt assembly 22 moves forwardly, a fresh cartridge 18, previously moved into receiver 14 from magazine 20, is picked up with the impact between claws 60 and the cartridge causing the claws to snap over the base thereof into extractor groove 62.

From the foregoing it is clearly apparent that there is provided herein a bolt assembly which is distinguished for its simplicity of design and economy of manufacture and which is positive in its functions.

Although a particular embodiment of the invention has been described in detail herein, it is evident that many variations may be devised within the spirit and scope thereof and the following claims are intended to include such variations.

I claim:

1. In a firearm having a receiver, the combination including a bolt mounted in the receiver for reciprocation between a recoil position and a battery position, a pair of extractors pivotally mounted on opposite sides of said bolt so as to carry a fired cartridge case rearwardly with said bolt to the recoil position, said extractors being respectively provided with an arm extending along the length of said bolt and an arcuate tail section extending across the rear end of said bolt, and means for actuating said extractor means to release the fired cartridge case when said bolt is in the recoil position, said actuating means including a buffer extending forwardly from the rear end so as to be contacted by said bolt when in the recoil position and by said tail section of each of said extractors, said tail section being formed so that when in contact with said buffer respective ones of said extractors are pivoted outwardly for release of the fired cartridge case.

2. The combination as defined in claim 1 wherein said arm is arranged to project outwardly from said bolt, and including channels formed inside of the receiver to slidably receive the projecting arm portion of said extractors for preventing angular displacement of said bolt around the longitudinal axis thereof during reciprocation in the receiver.

3. The combination as defined in claim 1 and including a firing pin disposed in said bolt for displacement therein between a cocked position and a striking position, and a spring arranged between said firing pin and said tail section of said extractors for simultaneously biasing said firing pin forwardly to the striking position and said extractors inwardly to engage said fired cartridge case.

4. The combination as defined in claim 3 and including a return spring disposed between said bolt and the rear end of the receiver for biasing said bolt to the battery position, and cocking means operationally disposed between said firing pin and the receiver to provide relative displacement of said bolt and said firing pin whereby said firing pin is cocked by the bias of said return spring during initial displacement of said bolt from the recoil position.

5. The combination as defined in claim 3 and including a return spring disposed between said bolt and the rear end of the receiver for biasing said bolt to the battery position, and cocking means operationally disposed between said firing pin and the receiver to provide relative displacement of said bolt and said firing pin whereby said firing pin is cocked by the bias of said return spring during initial displacement of said bolt from the recoil position.

6. The combination as defined in claim 5 wherein said cocking means includes a cocking lever pivotally mounted

on said firing pin for outward and forward extension through an opening in said bolt into a longitudinal channel formed inside the receiver, a cocking lever stop pin mounted in the receiver so as to transverse said channel and so as to be contacted by the free end of said cocking lever when said bolt is adjacent the recoil position for preventing displacement of said firing pin relative to said bolt during initial displacement thereof from the recoil positions, and a cocking lever release pin mounted through said bolt so as to transfer said opening and contact said cocking lever for pivotal displacement free of said cocking lever stop pin when said bolt is displaced respective to said firing pin to where said firing pin is located in the cocked position relative to said bolt.

7. The combination as defined in claim 6 and including a sear mounted in said bolt for engagement with said firing pin to releasably hold said firing pin in the cocked position relative to said bolt.
